ELECTRIC DAMPER CONTROL

Henry Carl Holz, Salt Lake City, Utah

Application August 1, 1945, Serial No. 608,283

4 Claims. (Cl. 236—74)

1

The invention relates to a control device, and more especially to a damper control apparatus for use in regulating pressure or boiler output.

The primary object of the invention is the provision of an apparatus of this character, wherein it is of electro-mechanical set-up, and automatically operated by the pressure from a boiler for controlling the damper thereof, and in this manner regulating the output of such boiler to assure constant steam pressure therefrom.

Another object of the invention is the provision of an apparatus of this character, wherein the construction thereof is novel and unique in the arrangement of its parts, it being electrically controlled and thus economical to operate, and without a complicated set-up exteriorly of the boiler.

A further object of the invention is the provision of an apparatus of this character, which is simple in construction, thoroughly reliable and efficient in operation, strong, durable, possessed of few parts, thereby making it economical to repair and replacement of parts, automatic in the working thereof, positive in operation, and inexpensive to manufacture and install.

With these and other objects in view the invention consists in the features of construction, combination and arrangement of parts as will be hereinafter more fully described, illustrated in the accompanying drawings, which show the preferred embodiment of the invention and pointed out in the claims hereunto appended.

In the accompanying drawings:

Figure 1 is a top plan view, partly broken away, showing the apparatus constructed in accordance with the invention in association with a boiler damper.

Figure 2 is a side view, partly broken away.

Figure 3 is a sectional view taken on the line 3—3 of Figure 2 looking in the direction of the arrows.

Figure 4 is a sectional view taken on the line 4—4 of Figure 1 looking in the direction of the arrows.

Figure 5 is a fragmentary detail elevation showing a slight modification.

Similar reference characters indicate corresponding parts throughout the several views in the drawings.

Referring to the drawings in detail, A designates generally a portion of an air pressure conduit from a fire box within a steam boiler, these being not shown, as the spirit of the invention contemplates its use to control any other boiler mechanism, such as a draft, blower engine, stoker

2

engine or the like, and also instead of being operated by pressure from the boiler, it could, if desired, be operated by changes in pressure in the fire box, or other variants in connection with the boiler, and in this instance, the operative is the pressure in the said fire box.

The conduit A is extended vertically within an oil font 10, which contains a determined quantity of oil 11, and working within the latter is a float 12 having a bell 13 movably telescoped onto the font 10, as best seen in Figure 2 of the drawings. This bell 13 is provided with a filling spout 14 fitted with a removable cap 15, so that oil can be introduced into the said font.

On a step 16 of a shelf 17 beneath the font 10 and to one side of the latter is a post 18 which rises vertically above the plane of the said font and bell 13 for swingingly supporting a counter-balancing lever 19, which is provided with an eye yoke 20 intermediate thereof for a clearance for the said post, the latter and the yoke being connected together by a horizontal pivot 21 for vertical swinging action of the lever 19. The shelf 17 is secured to a suitable support through the medium of brackets 11a.

Extending vertically centrally from the bell 13 is a hanger 22 to which is connected by a pivot 23 the lever 19, while at the outermost free end of the latter is fitted an adjustable weight 24 held in a set position by a set screw 25. Also connected to the hanger 22 at a point below the lever 19 is a secondary lever 26 which is also connected by a pivot 27 to the post 18 in parallelism with such lever 19. The lever 26 is connected 35 to the hanger 22 by a pivot 27a.

In vertical relation to the post 18 and spaced therefrom is a guide stand 28 having a worm feed screw 29 working therein, the latter at its upper end through the medium of a chain 30 has connection with a damper, not shown, for the regulation thereof and its control. This screw 29 has the spaced adjustable and stationary stops 31 and 32, respectively, while rotatably attached to the step 16 is a feed pulley wheel 33, which has threaded connection at its hub 34 with the screw 29 for the feeding thereof upwardly and downwardly to regulate the damper. The screw 29 is held against turning movement by vertical ribs 29a formed on the screw and slidably fitting 45 within vertical guides 28a within the stand 28, as shown in Figure 3.

On the shelf 17 is an electric motor 35 having its power shaft 36 fitted with a pulley 37 over which is trained an endless belt 38, which is also 55 trained over one of a pair of reduction pulleys

39 and 40, respectively, the other of these having an endless belt 41 trained thereover, and this belt being also trained over the wheel 33 for the driving of the latter.

Associated with the motor 35 is a magnetic reversing switch unit 42, which is supported on the shelf 17 and through an electric circuit system 43 having a strip switch 44 therein, is operated for the reversal of the motor. The switch 44 involves a throw blade 45 which is pivoted at 46 to the post 18 and also pivoted at 47 to a throw link 48, having pivoted thereto at 49 and 49a the trip arms 50 and 51, respectively, the former being acted upon by the adjustable stop 31, and the latter acted upon by the stationary stop 32 under the rise and fall of the screw 29, and such arms are rockingly attached on supports 52 and 52a above and below the stop 16.

Above the lever 19 and carried by the pivot 21 for the yoke 20 for disposition in the path of such lever 19 is a hand set weight 53, which can be manually thrown into one of three positions by a handle bar 54, one thrown position being shown by full lines in Figure 2 of the drawings, and the two other positions being shown by dotted lines in said Figure 2. The purpose of the weight 53 is to vary the activity of the lever 19 under variable pressures from the boiler, the pressure being trapped between oil level within the font 19 and the bell 13, as delivered thereto from the conduit A, as should be obvious. The weight 53 is secured to and between the swinging ends of arms 53a which are loosely connected to the pivot 21 of the lever 19. As shown, the weight is adapted to be swung into a neutral position directly above the pivot 21 or into an active position inwardly or outwardly of the pivot. When in said first active position, the weight 53 decreases the power of the weight 24 while when in said second active position, it adds to the power of the weight. The rod 54 is slidably mounted in guides 54a on the post 18 and has a forked upper end 54b provided with fingers 54c. The fingers 54c provide means which cooperate with one of the arms 53a during the manipulation of the rod 54 to move the weight in one of its three positions. The rod 54 is secured against accidental movement, to support the weight in its adjusted position, by a set screw 54d carried by a collar 54e, which is secured to the shelf portion 16 and through which the rod passes.

In Figure 5 of the drawings, there is shown a slight modification, wherein the worm screw wheel 55 is a substitute for the wheel 33, and this wheel 55 meshes with a worm screw pinion 56, for the feeding of the screw 29, the pinion being driven from the motor 57, and through the use of the wheel 55 and pinion 56 the pulleys and belts, as before described, are dispensed with.

It should be obvious that the motor is the power source for moving the damper, and on the travel of the screw 29 in an upward direction, the said damper is moved to one position and reverse downward travel of such screw 29 the said damper is moved to the other position. It should be seen that the damper will always take a definite relative position with respect to the then existing boiler pressure and retain this position until the boiler pressure changes, the damper being automatically controlled through the use of the apparatus constituting the present invention.

The screw 29 is prevented from rotating in the

stand 28 by a guide pin 51, as best seen in Figure 1 of the drawings.

What is claimed is:

1. An apparatus of the kind described, comprising a feed screw for connection with a damper to change its position, an electric motor, driving connections between the motor and screw, an electric circuit system having reversing means for the motor, pressure operated means cooperating with the screw and circuit system to control the reversing means of the latter to have the screw change the position of the damper, an oil font and bell therefor included in the pressure operated means, and adjustable and stationary feed limit means on the screw.
2. An apparatus of the kind described, comprising a feed screw for connection with a damper to change its position, an electric motor, driving connections between the motor and screw, an electric circuit system having reversing means for the motor, pressure operated means cooperating with the screw and circuit system to control the reversing means of the latter to have the screw change the position of the damper, an oil font and bell therefor included in the pressure operated means, adjustable and stationary feed limit means on the screw, and means manually regulated for changing the activity of the pressure operated means.
3. An apparatus of the kind described, comprising a feed screw for connection with a damper to change its position, an electric motor, driving connections between the motor and screw, an electric circuit system having reversing means for the motor, pressure operated means cooperating with the screw and circuit system to control the reversing means of the latter to have the screw change the position of the damper, an oil font and bell therefor included in the pressure operated means, adjustable and stationary feed limit means on the screw, means manually regulated for changing the activity of the pressure operated means, and adjustable counter-balancing means for the bell.
4. An apparatus of the character described, comprising a feed screw for connection with a damper to change its position, an electric motor, driving connections between the motor and the screw, an electric circuit system having reversing means for the motor, pressure operated means cooperating with the screw and circuit system to control the reversing means of the latter to have the screw change the position of the damper, an oil font and bell therefor included in the pressure operated means, adjustable and stationary feed limit means on the screw, and manually regulated means including a fulcrumed balance arm for changing the activity of the pressure operated means, said last named means comprising a weight which may selectively be placed in inoperative position and on either side of the fulcrum.

HENRY CARL HOLZ.
